UNITED STATES PATENT OFFICE.

HENRIK C. STRÄNG, OF CHICAGO, ILLINOIS.

ROD-PACKING.

SPECIFICATION forming part of Letters Patent No. 655,030, dated July 31, 1900.

Application filed June 30, 1898. Serial No. 684,824. (No model.)

To all whom it may concern:

Be it known that I, HENRIK C. STRÄNG, a citizen of the United States, residing at Chicago, in the county of Cook and State of Illinois, have invented certain new and useful Improvements in Rod-Packings; and I do hereby declare the following to be a full, clear, and exact description of the invention, such as will enable others skilled in the art to which it applies to make and use the same.

This invention relates to an improved arrangement for use on engines where the motive agent is of a high pressure and temperature and is especially adapted for use on gas engines.

Heretofore serious difficulties have been encountered in operating certain types of engines for the want of a suitable packing and stuffing box.

The object, therefore, of this invention is to provide an arrangement of this character in which the rod works through a space or chamber in which water is made to circulate. Any other liquid or suitable lubricating substance may be employed, but ordinarily the water circulation will be preferred. The metallic rod-packing is automatically adjustable to compensate for the wear and action of the rod, so that a close-fitting joint is always assured with the least friction possible.

Figure 1 is a broken-away longitudinal section showing a part of an engine-cylinder, the piston-rod and packing being shown in working order. Fig. 2 is a longitudinal section through the line of the stuffing-box and packing, the piston-rod being shown in elevation. Fig. 3 is an elevation of one of the adjacent inside follower end packing-rings. Fig. 4 is an elevation of an inside sectional ring placed next to the solid end ring. Fig. 5 is an elevation of one of the inside sectional rings. Fig. 6 is an elevation of a companion outside ring. Fig. 7 is an elevation of a sectional end ring. Fig. 8 is a section showing two of the sectional rings that bear on each other, the division-lines being shown in different planes. Fig. 9 is a section of the ring shown in Fig. 3. Fig. 10 is a section of the ring shown in Fig. 4. Fig. 11 is a section of the ring shown in Fig. 5. Fig. 12 is a section of the ring

shown in Fig. 6, and Fig. 13 is a section of the ring shown in Fig. 7.

A may represent the cylinder of an engine; A', the water jacket or casing surrounding the same; A², the cross-head; A³, the casting supporting the cylinder and cross-head, and A⁴ the piston-rod.

The stuffing-box is what might be termed a "double" one, being divided into two parts with a space between. A full set of packing rings is placed in each part. The part B or outer stuffing-box is detachably secured in position by a number of tap-bolts a, seating in the inner end of the water-jacket. The inner part B' of the stuffing-box is formed in the end of the engine-cylinder by thickening the casting at that point, as shown in Figs. 1 and 2. This arrangement provides for the water space or chamber B², into which the circulating-passages a' a' open from the water-space a², between the cylinder and its inclosing jacket. a³ may represent the inlet and a⁴ the outlet connection for maintaining the circulation of the water or other liquid cooling agent. This circulation may be maintained by gravity or a forced mechanical operation, as the conditions under which the engine is working may require. The two sets of metallic packing-rings used in the two-part stuffing-box are exact duplicates, so

that a description of one set will answer for both, the same reference characters being used on companion rings in each set. The inner adjacent follower or companion rings b are solid and are cut away on their outer side to provide a shoulder-bearing b' to receive the ends of the coil-spring b², surrounding the piston-rod, and support the same away from frictional contact therewith. The inner face of the solid follower-ring b is cut away at an angle, forming the beveled surface b³. The joining face of the next ring b⁴ is cut away at a corresponding angle. The periphery of this ring b⁴ is cut away at an inwardly or downwardly sloping angle from the point of contact with its outside follower-ring to its inner edge of but little thickness and forms a ring that is approximately of a triangular shape in cross-section. The inner straight circumferential surface of the ring

b^4 has frictional contact with the piston-rod. Next to the ring b^4 is placed the ring d , which is of a corresponding shape in cross-section, but is seated in a reversed position, the inner beveled surface bearing on the correspondingly-beveled surface of the ring b^4 , the straight surface or periphery d' being next to the inclosing wall of the stuffing-box. Next to the ring d is its companion ring d^2 , the inner abutting ends of these two companion rings coming together on a vertical line d^3 . The beveled surface of the ring d^2 has contact with the correspondingly-beveled surface of the ring d^4 , which is a duplicate companion ring of the ring b^4 . An annular space d^5 is left between the inner adjacent wedge-shaped ends of the rings b^4 and d^4 , so as to provide for the adjustment in compensating for the wear. This adjustment is automatically accomplished by the constant pressure of the spring b^2 . Thus a series of four rings forms a set of packing-rings proper, and each ring is divided into three segmental sections on the two vertical planes g and g^2 , each approximately one-half the depth of the ring, and a horizontal plane surface g' , connecting the two vertical plane surfaces and forming overlapping joints. These ring-sections are loosely joined together with reference to each other, but form a tight joint against the entrance of water from the circulating-passages. This division of the rings also adapts them to automatically conform to any irregularities in the working conditions of the piston-rod, such as the rod being out of line. The tension of the spring is proportionately divided between the two sets of rings, so that the adjustment maintained is uniform. Instead of dividing each ring of the series into three sections they may be divided into two parts or more, as will be the most suitable for different types of engines, and I do not therefore limit myself to the precise construction and arrangement shown.

45. The series of rings are provided with threaded tap-holes g^3 for the connection of a suitable tool in putting in or taking out the rings. When inserting the rings, they will be so placed that the division-lines will be in different planes, so as to break joints.

The outer end of the stuffing-box is closed by a gland C, having its inner face beveled at an angle corresponding to and fitting the adjoining face of the first packing-ring. This gland is provided with an oil-chamber h , from which the piston-rod may be lubricated.

55. The circulating cooling fluid through the chamber or space surrounding the piston-rod is continuous, so that a cooling temperature is always maintained.

I do not confine myself to the two-part stuffing-box arrangement shown, but may use one set of rings under the usual or ordinary conditions, especially in steam and other types of engines not having so high a temperature as to require the circulating cooling

feature in order to keep the piston-rod in a good working condition.

Having thus described my invention, what I claim as new, and desire to secure by Letters Patent, is—

1. A two-part stuffing-box, having a complete set of packing-rings in each part and separated by a chamber or space surrounding the piston-rod and opening into the water-space between the engine-cylinder and its inclosing jacket, substantially as described. 75

2. A two-part stuffing-box, having a complete independent set of packing-rings in each part and separated by a chamber or space the inclosing walls of which are exterior to that of the walls of the stuffing-box and having passages communicating with the water-space between the engine-cylinder and its inclosing jacket, whereby a continuous circulation of a cooling fluid is brought in contact with the piston-rod common with that of the circulation between the cylinder and inclosing jacket, substantially as described. 80

3. The combination with a stuffing-box, of a chamber or space dividing the stuffing-box into two parts and opening into the water-space between the engine-cylinder and jacket, whereby a continuous circulation of a cooling fluid is brought in contact with the piston-rod, substantially as described. 85

4. A stuffing-box, divided into two parts, one part of which is formed in the end of the engine-cylinder, the other part being detachable and independent therefrom, said two parts being separated by a chamber or space communicating with the water-space of the engine-cylinder and inclosing jacket and providing for a continuous circulation of a cooling fluid having contact with the piston-rod, substantially as described. 90

5. The combination in a two-part stuffing-box, one part of which is formed in the engine-cylinder and the other part independent and detachable therefrom, the dividing chamber or space providing for a continuous circulation of a cooling liquid, the independent sets of packing-rings, the piston-rod, and the spring, encircling said rod and having its respective ends bearing on and compressing each set of packing-rings, substantially as described. 95

6. A two-part stuffing-box, each part being constructed separably from the other and provided with independent sets of packing-rings, a liquid-cooling chamber, formed between and exteriorly to the walls of each of said parts and through which a continuous circulation is maintained, the piston-rod, working therethrough, and a coiled spring, located outside of either part of the stuffing-box and encircling the piston-rod but supported out of contact therewith and in position to exert a tension on both sets of packing-rings alike and hold the same in place and automatically compensate for the wear so as to uniformly maintain a tight joint, substantially as described. 100

7. The combination with a stuffing-box, divided transversely by a liquid-cooling chamber or space whose walls are exterior to the walls of the box proper, of the two sets of 5 packing-rings located on each side of and separated from each other by said cooling-chamber, the piston-rod, and the coiled spring, located in said cooling-chamber and encircling said rod and adapted to divide its ten-

sion, and press against the two sets of packing-rings alike, substantially as described.

In testimony whereof I affix my signature in presence of two witnesses.

HENRIK C. STRÄNG.
